AIRCRAFT BOMB EQUIPMENT

Estil Irvin Fenton, Los Angeles, Calif.

Application September 19, 1941, Serial No. 411,501

4 Claims. (CL 89—1.5)

This invention relates to aeronautical bomb equipment and it is a general object of this invention to provide a practical, effective bomb mechanism by means of which a bomb or explosive charge carrying element may be suspended from an aircraft to be brought into contact with or to be grappled with an enemy craft to destroy or disable the same.

Another object of this invention is to provide means useful on pursuit craft, fighter craft and the like, operable to suspend a bomb or explosive charge carrying element from the craft when in flight to be brought into contact with or to be entangled with an enemy craft or other objective to destroy the same.

Another object of this invention is to provide apparatus of the character mentioned by means of which the bomb or explosive element may be suspended any selected distance from the aircraft at the required or wanted time and in which the explosive element may be returned to the carrier craft in the event it proves unnecessary or in the event contact is not made with the enemy aircraft or other objective.

Another object of this invention is to provide an apparatus of the character mentioned in which the bomb or explosive charge carrying element is of such design that it remains suspended below the aircraft with which it is associated even though said craft may be traveling at a high rate of speed.

Another object of this invention is to provide an apparatus of the character referred to embodying a safety means for releasing the reel which carries the suspension line of the bomb or explosive element when the line becomes entangled with or is forcibly contacted by the enemy aircraft or other objective. The safety means releases only upon the line being subjected to a heavy strain resulting from the contact of the line or bomb, or both, with the enemy plane, or other objective, thus insuring the most effective engagement of the line and explosive element with the enemy craft and permitting the line to wrap or swing about parts of the enemy craft to bring the explosive charge element or bomb into contact therewith. The release of the spool or reel prevents injury to the mechanism which may remain as a permanent installation on the aircraft.

A further object of this invention is to provide an apparatus of the character mentioned embodying novel means for automatically racking or retaining the bomb or explosive charge carrying element in position at the under side of the craft for

subsequent use when returned or reeled in after being suspended by its line.

The various objects and features of my invention will be fully understood from the following detailed description of a typical preferred form and application of my invention, throughout which description reference is made to the accompanying drawings, in which:

Fig. 1 is a perspective view showing the bomb or charge carrying element suspended from its carrier aircraft in position to strike or grapple with an oncoming enemy craft. Fig. 2 is an enlarged perspective view of the bomb or charge carrying element in flight or suspended by its line. Fig. 3 is an enlarged longitudinal vertical detailed sectional view of the line handling mechanism and the bomb racking and control means of the invention. Fig. 4 is a fragmentary plan view of the equipment illustrated in Fig. 3. Fig. 5 is a sectional view illustrating the loop or ring for cooperating with the suspension members of the bomb, being a view as indicated by line 5—5 on Fig. 3. Fig. 6 is an enlarged vertical detailed sectional view taken as indicated by line 6—6 on Fig. 3 and Fig. 7 is a fragmentary side elevation illustrating the bomb or charge carrying element in its normal position at the under side of the aircraft.

The present invention may be embodied in forms for use on aircraft of various types and may be modified considerably to suit it for given applications and installations. In the drawings I have illustrated a typical form of the invention installed on an aircraft A of conventional design, it being understood that the present invention is not to be construed as limited or restricted to the specific form or application herein described, but is to be taken as including any features or modifications that may fall within the scope of the claims.

The apparatus of the invention may be said to comprise, generally, a bomb or explosive charge carrying element 10, a suspension line 11 for the element 10, line reeling or handling means 12 for reeling in the line 11 and for controlling the unreeeling of the line and control elements and safety features associated with the means 12, the functions and details of which will be later described.

The bomb or explosive charge carrying element 10 may, in accordance with the broader aspects of the invention, take various forms and may be modified in character to adapt it for given uses. As illustrated, the bomb or element 10 comprises an elongate torpedo-like shell or body 13 of streamline design tapered longitudinally to have

pointed forward and rearward ends. It may be considered that the body 13 is round in transverse cross section, although this shape may be varied as required. The bomb or element 10 is provided at its tail or rear portion with a plurality of stabilizing rudders or fins 14 to prevent the element from turning about its longitudinal axis and for holding it on a straight forward course when suspended from the moving craft A. In the drawings there are four fins 14, two lying in a generally horizontal plane and two disposed in a generally vertical plane. The invention provides means for holding or maintaining the bomb or element 10 below the aircraft A even though the latter may be traveling at a very high speed. Wings or blades 15 project from opposite sides of the bomb body 13. The blades 15 are pitched, that is, they lie in planes which slope downwardly and forwardly relative to the longitudinal axis of the torpedo-like body 13. The pitch of the blades 15 tends to cause the charge carrying element 10 to nose down and counteracts or overcomes the tendency for the element 10 to trail behind the rapidly moving aircraft A. The size and pitch of the blades 15 may be related to the size and weight of the element 10 and the intended or probable speed of travel to hold the element 10 substantially directly below the aircraft A. The explosive charge carrying element 10 may be such that it explodes upon contact or impact, in which case it may be considered that the nose 16 of the body 13 carries cap means, or the like, for setting off the charge upon contact or, if desired, the element 10 may have a timing mechanism to explode a given time after being lowered from the aircraft A. The present invention is not primarily concerned with the details of the charge or the charge firing means of the element 10, as these details are well known to those skilled in the art.

The line 11 serves to suspend the explosive charge carrying element 10 from the aircraft A when the element is to be put into use. The line 11 is an elongate flexible member such as a wire, cable, or the like. The length of the line 11 may be varied with different intended uses of the apparatus but, in most cases, it is preferred to make the line 11 of substantial length so that the explosive charge carrying element 10 may be lowered a considerable distance from the aircraft A to lessen the possibility of injury to the aircraft A which may result from an explosion of the element 10 or from the weapons of the enemy craft. In accordance with the invention, the line 11 has high tensile strength. For example, where the element 10 weighs approximately 25 pounds I prefer to employ a line 11 having a tensile strength of about 1500 pounds. When the line 11 has a high tensile strength it may be contacted or engaged by the rapidly moving enemy craft B without failing and will thus remain intact to cause the explosive charge carrying element 10 to be brought into forcible contact with or close proximity to the craft B when the line swings about the engaging part of the aircraft B. It is preferred to employ a line 11 of minimum diameter and of minimum weight with the required or desired tensile strength in order to reduce the size of the reeled line and to reduce the weight of the equipment to a minimum.

It is preferred to provide means for coupling or connecting the line 11 with the element 10 in such a way that the element will remain stabilized and in a generally horizontal forwardly projecting position when closely coupled with the

aircraft A and to remain in the "flight" position when suspended by means of the line 11. While various means may be employed to connect the line 11 with the element 10 I have illustrated a simple structure comprising a series of guy members or cables 17 attached to the element 10 and have shown the line 11 secured to these cables. As best illustrated in Fig. 2 of the drawings, there may be a cable 17 secured to the body 13 adjacent its nose 16, a cable 17 secured to the body 13 at a point behind the wings or blades 15 and a cable 17 secured to each wing 15. The cables 17 extend upwardly in converging relation and their upper ends may be rigidly secured or tied together. The line 11 is connected with the cables 17 at this point of connection of the cables by a suitable clamp means or by tying. The positioning and formation of the members or cables 17 are such that the explosive charge carrying element 10 has no tendency to nose up or nose down or to turn about its longitudinal axis when suspended from the line 11. In most cases it will be found desirable to provide suspension members or cables 17 on the forward portion of the element 10.

The line controlling and spooling means 12 is mounted on the craft A preferably being positioned at the under side of aircraft. The means 12 includes a suitable supporting frame 18 of tubing, or the like, fixed to the aircraft A. In practice, the frame 18 may be mounted in a pocket in the body or fuselage of the aircraft A. The frame 18, as illustrated, is a generally rectangular structure and is open at its several sides. A block or disc 19 is fixed in the upper portion of the frame 18 and has a longitudinal or axial opening 20 carrying a freely rotatable shaft 21. The shaft 21 is held against endwise movement by pins 22 in the hub of the disc 19 cooperating with a groove in the shaft. The shaft 21 extends rearwardly beyond the disc 19 and a suitable universal joint 23 connects the rearwardly projecting part of the shaft with the reel shaft or spool shaft 24. The shaft 24 is formed with or carries a cone 25. The cone 25 tapers or converges rearwardly to a stub shaft portion 26. A plurality of spaced longitudinal keys or splines 27 is provided on the cone 25. A reel or spool 26 is removably slid forwardly on the cone 25 and its internal surface is shaped to conform to the tapering cone. Keyways or grooves 28 in the interior of the spool 28 receive the splines 27 so that the spool is held against rotation relative to the cone and shaft 24. The line 11 is reeled on the spool 28 and passes downwardly to the element 10, as will be more fully described. It may be preferred to provide a guide pulley or roller 30 in the lower portion of the frame 18 to direct or guide the downwardly extending line 11.

Releasable safety means is provided to initially and normally support the rear end of the spool shaft 24 where the spool and shaft 24 are aligned with the shaft 21. This safety means is releasable by a heavy pull on the line 11 such as may result from the engagement of the line 11 with the enemy craft B and allows the spool to become detached from the mechanism to prevent injury to the permanent equipment. The frame 18 carries a support or bracket 31 having a forwardly facing socket 32 for receiving the stub shaft 26. The lower portion of the bracket 31 is forked or yoked and is open to the under side of the socket 32. A latch 33 is arranged in the yoked portion of the bracket 31 and is pivotally supported by a substantially horizontal pivot pin 34. The latch

33 is provided with an upper face 35 serving to carry or support the stub shaft 26, the surface constituting the lower wall of the stub shaft socket 32. A lever 36 projects rearwardly from the latch 33 and a spring 37 is connected between the lever 36 and a suitable part of the frame 18. I have shown the lower end of the spring 37 secured to an adjustable anchor 9. The spring 37 is under tension and serves to hold the latch 33 in the position where its surface 35 maintains or supports the stub shaft 26. The shaft supporting face 35 is adjacent the pivotal axis of the latch 33 and the lever 36 and the spring 37 are proportioned so that a heavy force is required to overcome the spring 37 and permit disengagement of the stub shaft 26 from the latch. In practice, a downward force of say 1000 pounds transmitted from the stub shaft 26 to the surface 35 may be required to swing the latch 33 downwardly and rearwardly to permit the stub shaft to swing free of the latch. The rear end of the stub shaft 26 is preferably rounded and the forward end of the latch 33 is similarly rounded so that the stub shaft may swing clear of the latch when the force on the line 11 overcomes the spring 37.

Means may be provided for guiding the spool 28 clear of the means 12 when the yielding support or latch 33 is released as above described. A chute or guide member 38 curves downwardly and forwardly from adjacent the upper nose portion of the yielding support or latch 33 and continues downwardly to adjacent the guide roller 30 for the line 11. When the yielding support or latch 33 swings downwardly and rearwardly under a heavy force transmitted by the stub shaft 26 the cone 25 and the spool 28 swing downwardly and forwardly while they continue to rotate, assuming there is a pull on the line 11 which tends to cause rotation. This action is permitted by the universal joint 23. The guide member 38 directs the spool 28 downwardly and prevents it from fouling with the frame 18 or other parts and the spool is allowed to fall or pass clear of the frame, etc.

The means 12 further includes a brake mechanism associated with the shaft 21 to control or resist unwinding of the line 11 and lowering of the element 10. The above mentioned disc 19 forms one element of the brake means having a forwardly directed annular braking surface 40 which may be provided with suitable friction material. A shiftable brake disc 41 has a similarly formed and equipped surface 42 for cooperating with the surface 40. The disc 41 has a hub 43 slidably connected with the shaft 21 by splines 44. A ring 45 is rotatably received in an annular groove in the hub 43. Pins 46 are fixed to the ring 45 and pass rearwardly through openings in the disc 19. Heads 47 are provided on the rear ends of the pins 46 and springs 48 are arranged under compression between the heads 47 and the rear face of the disc 19. The springs 48 serve to urge the brake disc 41 rearwardly to maintain the braking surfaces 40 and 42 in cooperation to resist or prevent rotation of the shaft 21 and the spool 28.

The spring held or spring actuated brake means just described may be such that it offers substantial resistance to rotation of the spool 28. In a typical case the brake means may resist a pull on the line 11 up to a maximum pull of 500 pounds, this being less resistance than offered by the yielding support or latch 33 so that where there is line remaining on the spool 28 the brake

means may merely resist, or offer a drag to, a pull on the line 11 of a magnitude greater than 500 pounds. With a pull on the line 11 of between 500 and 1000 pounds the line may unreel from the spool 28 but is resisted by the action of the spring actuated brake means.

Manual means is provided for releasing the brake to allow free or controlled unreeling of the line 11 and lowering of the element 10 and to provide for reeling in of the line 11 and the explosive charge carrying element 10. The brake releasing means includes a fork 49 pivotally supported in the frame 18 by a pivot pin 50 and having spaced fingers 51 for cooperating with the heads 47 of the pins 46. A lever 52 is provided on the fork 49 and projects from the frame 18 to be accessible for manual operation. When the lever 52 is moved rearwardly the springs 48 are compressed and the brake disc 41 is shifted forwardly. This disengages or partially disengages the braking surfaces 40 and 42 to permit rotation of the spool 28 for the unreeling of the line 11 or for reeling in the line 11, as the case may be.

25 The means for reeling in the line 11 and the explosive charge carrying element 10 includes a shaft 53 rotatably supported by a bearing 54 carried by a front member 55 of the frame 18. A suitable operating handle or crank 56 is fixed on the forward end of the shaft 53. A clutch disc 57 is slidably but non-rotatably connected with the shaft 53 by splines 58 and opposes the forward side of the brake disc 41. A head 59 on the shaft 53 limits the rearward movement of the disc 57. The brake disc 41 and the clutch disc 57 have cooperable opposing surfaces 60 which may be provided with friction material. A spring 61 surrounds the shaft 53 and is arranged under compression between the bearing 54 and the hub of the disc 57 to yieldingly hold the disc in its rearward position against the head 59 for engagement by the brake disc 41. When the brake disc 41 is released from the stationary disc 19 the forward movement of the brake disc 41 may carry its surface 60 into cooperation with the surface 60 of the clutch disc 57 so that rotation of the crank 56 may reel in the line 11. This operation will be later described in more detail.

50 The apparatus preferably includes a control for automatically racking or positioning the charge carrying element 10 when the same is reeled back to the aircraft A. This control includes an elongate tube 62 provided at its upper end with a bearing 63 which pivotally and slidably rides on a transverse lower member 64 of the frame 18. The lower end of the tube 62 has a tubular guide bushing 65 and a rod 66 slidably passes through the bushing 65. The rod 66 is preferably polygonal and fits a correspondingly shaped opening in the bushing 65. A tubular guide 67 is fixed within the tube 62 to slidably guide the upper portion of the rod 66. A head or stop 68 is fixed to the rod 66 and is engageable with the inner end 65 of the bushing 65 to limit the outward movement of the rod. A spring 69 is arranged under compression between the guide 67 and the stop 68 to yieldingly urge the rod 66 to its outermost position illustrated in Fig. 3.

70 A line receiving ring 70 is fixed on the outer end of the rod 66. The ring 70 has a gap 71 in its upper side to receive the line 11. The ring 70 cooperates with the guy members or cables 17 of the element 10 as will be later described. A handle 72 is secured to the upper end of the

tube 62 so that the tube may be swung between a position such as illustrated in Fig. 3 and a retracted position clear of the line 11 and the guide member or chute 38 and so that the tube 62 may be slid or shifted along the member 64 to bring the ring 70 into alignment with the line 11. When the line 11 is reeled in by rotation of the crank 56 the tube 62 is positioned substantially as shown in Fig. 3 and when the element 10 approaches the aircraft A the guy cables 17 contact the ring 70. The upper portions of the convergent guy cables 17 enter the ring 70 and the contact or engagement shifts the rod 66 upwardly against the spring 69.

The invention preferably includes a safety control for limiting or stopping reeling in of the line 11 and upward movement of the element 10 when the guy cables 17 contact the ring 70 and shift the same upwardly as just described. This safety control includes a latch 73 for releasably latching the fork 49 in a position where it holds the brake disc 41 released from the stationary disc 19 and in cooperation with the clutch disc 57. The latch 73 is pivotally mounted in the frame 18, by a pivot pin 74, to cooperate with a face 75 on the fork 49. A spring 76 urges the latch 73 to the position where it cooperates with the face 75. When the fork 49 is moved to the position illustrated in full lines in Fig. 4 to release the brake and to engage the clutch for reeling in of the line 11, the latch 73 cooperates with the face 75 to retain the fork 49 in this position.

The latch 73 is automatically released when the explosive carrying element 10 reaches its correct position at the under side of the aircraft A. A lever 77 is pivotally mounted on the upper portion of the tube 62 and extends inwardly through a slot in the tube to be engaged by the rod 66 when the latter is moved upwardly by the contact of the guy cables 17 with the ring 70. A suitable guided and protected wire 78 is connected with the outer end or arm of the lever 77 and extends to an arm on the latch 73. When the charge carrying element 10 approaches its correct position at the under side of the aircraft A the guy cables 17 engage the ring 70 to move the rod 66 upwardly. The upper end of the rod engages and pivots the lever 77 pulling the wire 78. The pull on the wire 78 pivots the lever 77 to its released position clear of the surface 75 and the springs 48 return the fork 49 to its normal position and bring the brake disc 41 against the stationary disc 19 to stop rotation of the spool 28 and thus position and hold the element 10 in the correct racked position.

In the use or operation of the apparatus the element 10 is initially set in the position illustrated in Fig. 7 of the drawings where its cables 17 hold the ring 70 and the rod 66 in their uppermost positions. In this connection it will be observed that the tube 62 may swing to a substantially upright position and that the spring 69 exerts a stabilizing force on the cables 17 to hold the element 10 steady. The plurality of cables 17 engage in the ring 70 to further stabilize and steady the element 10. The means 12 is in the condition illustrated in Fig. 3 with the brake disc 41 in cooperation with the stationary disc 19 to hold the element 10 in its racked position. With the parts in this condition the aircraft may take off and may be operated in the usual way without danger of displacing the bomb or element 10.

When the aircraft A comes to a position where it may fly above an enemy craft B, either travel-

ing in the same direction or in the opposite direction, it is maneuvered to pass directly over the craft. Prior to the time when the aircraft A passes over the enemy craft B, or other objective, the handle or lever 52 is operated to pivot the fork 49 and release or partially release the brake. The brake disc 41 may be shifted forwardly a sufficient extent to allow the line 11 to unreel from the spool 28 under the weight of the element 10. The explosive carrying element 10 may be allowed to lower the required distance where it will either strike the enemy craft B or will be a selected distance below the enemy craft or objective. The lever 52 may be returned to the position where the brake is set. The pilot of the aircraft A may maneuver the same to bring the element 10 into contact with the objective or enemy craft B. If this occurs the element 10 explodes to destroy or disable the enemy craft.

The aircraft A may be maneuvered to cause the line 11 to be struck by a part of the objective or enemy craft B some distance above the element 10 so that the element will be swung up to directly contact the enemy craft and explode, to destroy or disable the enemy craft. In the event that neither the element 10 nor the line 11 contacts the objective it may be desired to leave the element 10 suspended from the aircraft A for a second attempt to contact with the objective or for contacting another objective. In this connection it is to be observed that the fins or blades 15 overcome the tendency for the element 10 to trail behind the aircraft A and hold the element 10 below the aircraft in position for use.

In the event the line 11 is struck by or tangled with the objective or enemy craft B as above described, the line may be subjected to a heavy tensile strain. In some cases this tensile strain may only be sufficient to overcome the resistance offered by the brake means, in which case, the spool 28 will rotate against the resistance offered by the brake to relieve the strain. In other cases, the strain may be of greater intensity and may be sufficient to overcome the spring 37. In this case, the yielding support or latch 33 pivots downwardly to allow the spool shaft 24 and the spool 28 to swing downwardly and forwardly. The spool 28 is free to slide from the cone 25. Thus, a heavy strain which may injure the equipment results in the release of the spool 28 saving the equipment from harm. It is to be observed that the line 11 is sufficiently strong to withstand strains of greater value than those which will release the spool 28.

In the event the attempts to contact the enemy craft or objective with the line 11 or element 10 are unsuccessful the element 10 should be returned to its racked position at the under side of the aircraft A. To accomplish this the tube 62 is brought to a position such as shown in Fig. 3 and the lever or handle 52 is swung to the position where the brake disc 41 is released from the stationary disc 19 and is brought into contact with the clutch disc 57. The brake disc may be moved forwardly sufficiently to fully clear the stationary disc 19 and to cause retraction of the clutch disc 57 against the action of the spring 61, the spring 61 serving to maintain a desirable clutching engagement between the discs 41 and 57. The crank 56 is then operated to reel in the line 11 on the spool 28. As above described, the latch 73 will automatically retain the fork 49 in the position where the brake disc 41 is released from the stationary disc 19 and is held in clutching engagement with the clutch disc 57.

The line 11 is reeled in until the guy cables 17 engage the ring 70 and shift the ring 70 and rod 68 upwardly so that the rod shifts the lever 77. Pivoting of the lever 77 results in release of the latch 73 and the brake disc 41 is automatically brought into braking engagement with the stationary disc 19 to stop the spool 28 in the position where the element 10 is correctly racked or retained under the aircraft A. The apparatus is thus returned to its normal condition and is ready for re-use.

Having described a typical preferred form and application of my invention, I do not wish to be limited or restricted to the specific details herein set forth, but wish to reserve to myself any variations or modifications that may appear to those skilled in the art or fall within the scope of the following claims:

Having described my invention, I claim:

1. In apparatus for use on an aircraft having an explosive charge carrying element, a flexible line for suspending the element and a spool for the line, means rotatably mounting the spool on the aircraft, releasable brake means for controlling rotation of the spool, releasable to allow the line to spool out and the element to lower from the aircraft, releasable means for holding the brake means in the released condition, means for rotating the spool to reel in the line, and means for automatically releasing said releasable means to make the brake means effective when the element has been returned to its original position.

2. In apparatus for use on an aircraft having an explosive charge carrying element, a flexible line for suspending the element and a spool for the line, the combination of, a shaft carried by the aircraft for receiving and holding the spool so it is readily detachable therefrom to release the spool from the aircraft, manually controllable means for allowing rotation of the spool to per-

mit lowering of the element and to stop rotation of the spool with the element in selected positions, and means normally preventing detachment of the spool releasable by a strain on the line of a value less than that required to break the line.

3. In apparatus for use on an aircraft having an explosive charge carrying element, a flexible line for suspending the element and a spool for the line, the combination of, a shaft carried by the aircraft for receiving and holding the spool so it is readily detachable therefrom to release the spool from the aircraft, manually controllable means for allowing rotation of the spool to permit lowering of the element and to stop rotation of the spool with the element in selected positions, the manually controllable means allowing rotation of the spool when the line is subjected to a heavy strain, and means normally preventing detachment of the spool releasable by a strain on the line greater in value than that required to cause rotation of the spool when said manually controlled means is holding the spool against movement.

4. In apparatus for use on an aircraft having an explosive charge carrying element, a flexible line for suspending the element, a spool for the line and means rotatably mounting the spool on the aircraft, the combination of, releasable brake means for controlling rotation of the spool, releasable to allow the line to spool out and the element to lower from the aircraft, a releasable latch for holding the brake means in the released condition, means for rotating the spool to reel in the line, a lever operatively connected with the latch, a movable member for operating the lever to release the latch, and a part on the line adjacent said element for operating the lever to make the brake means effective when the element has been returned to its original position.

ESTIL IRVIN FENTON.
